(57) **CLAIM**

The ornamental design for a backlit faceplate for computer cabinet, as shown and described.

DESCRIPTION

FIG. 1 is a perspective front view of a backlit faceplate incorporating my design, shown installed on a computer;

FIG. 2 is a perspective front view of the faceplate, shown removed from a computer;

FIG. 3 is a perspective front view of the faceplate;

FIG. 4 is a perspective rear view of the faceplate;

FIG. 5 is a front elevation of the faceplate;

FIG. 6 is a rear elevation of the faceplate;

FIG. 7 is a top view of the faceplate;

FIG. 8 is a bottom view of the faceplate;

FIG. 9 is a left-side elevation of the faceplate; and,

FIG. 10 is a right-side elevation of the faceplate.

The portions of the backlit faceplate for computer cabinet shown in broken lines form no part of the claimed design.

The jagged broken line surrounding the message window in FIGS. 1, 2, 3, and 5 indicates that the message window is illuminated and this illumination is part of the claimed design.
